US00D372002S

United States Patent [19]

Busby et al.

[11] Patent Number: Des. 372,002

[45] Date of Patent: **Jul. 23, 1996

[54] BICYCLE FRAME

[75] Inventors: **James S. Busby**, Costa Mesa; **Steven H. Olson**, Corona; **Stanley A. Needle**, Irvine; **Sean W. Flickinger**, Costa Mesa; **Jeffrey A. Soucek**, Huntington Beach, all of Calif.

[73] Assignee: **GT Bicycle, Inc.**, Santa Ana, Calif.

[**] Term: 14 Years

[21] Appl. No.: 43,245

[22] Filed: Aug. 23, 1995

[52] U.S. Cl. D12/111

[58] Field of Search D12/111; 280/281.1, 280/288.1, 288.2, 288.3

[57] CLAIM

The ornamental design for a bicycle frame, as shown and described.

DESCRIPTION

FIG. 1 is a front perspective view of the bicycle frame of the present invention, showing our new design;

FIG. 2 is a rear perspective view thereof;

FIG. 3 is a right side elevational view thereof;

FIG. 4 is a left side elevational view thereof;

FIG. 5 is a cross-sectional view taken along line 5—5 of FIG. 3;

FIG. 6 is a rear elevational view thereof;

FIG. 7 is a front elevational view thereof;

FIG. 8 is a top plan view thereof; and,

FIG. 9 is a bottom plan view thereof.
